UNITED STATES PATENT OFFICE.

JOHN O. NYMAN AND JOHN P. PEARSON, OF CANTON, OHIO.

SHEET-METAL PARTITION.

1,417,102.

Specification of Letters Patent. Patented May 23, 1922.

Application filed May 29, 1920. Serial No. 385,177.

To all whom it may concern:

Be it known that we, JOHN O. NYMAN and JOHN P. PEARSON, both subjects of the King of Sweden, and both residing at Canton, Stark county, Ohio, have jointly invented new and useful Improvements in Sheet-Metal Partitions, of which the following is a specification.

This invention relates to improvements in partition construction and more particularly to a portable partition composed of sheet metal.

The objects of the invention are to provide a partition which may be easily or readily assembled or knocked down, which may be located in any desirable position within a building, there being no permanent connection between any portions of the partition, the arrangement of the partition being such that it may be easily and readily shipped; a novel attaching device being provided by which the uprights of the partition are held firmly in position; other objects being the provision of a simple, inexpensive and durable partition of the construction referred to.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

The invention thus set forth in general terms is illustrated in the accompanying drawings forming part hereof, in which—

Figure 1 is a side elevation of a portion of a partition constructed in accordance with the invention.

Fig. 2 is a section on the line 2—2, Fig. 1.

Fig. 3 is a section on the line 3—3, Fig. 1.

Fig. 4 is a section on the line 4—4, Fig. 1.

Fig. 5 is a section on the line 5—5, Fig. 1.

Fig. 6 is a section on the line 6—6, Fig. 1.

Fig. 7 is a section on the line 7—7, Fig. 1;

and

Fig. 8 is a section on the line 8—8, Fig. 6.

A practical embodiment of the invention is disclosed in the accompanying drawings, forming a part of this specification in which similar numerals of reference indicate cor-

responding parts throughout the several views.

The partition which is herein described is of the portable or knock-down type and is composed of a frame work comprising a plurality of suitable uprights and horizontal connecting rails within which are assembled panels which may be formed of sheet metal or glass sashes as may be desired.

The partition is particularly designed for use in large offices, factories and the like where it is often necessary and desirable to change the interior arrangement of rooms and this may be accomplished by the moving or rearranging of the partitions which will be hereinafter described.

The frame work of the partition is built up of spaced uprights which are fixedly mounted between the floor and the ceiling, said uprights being connected at spaced intervals by horizontal rails.

Each of the uprights is formed of two identical channel members designated by the numeral 1, each of said channel members being provided along its longitudinal center with an inwardly disposed dove-tailed channel 2 of less depth than the channel member proper. Each channel member 1 is preferably provided at each side of the dove-tail channel portion 2 with an off-set portion 3 provided for the purpose of further reinforcing the uprights.

The horizontal connecting rails are of the same cross sectional shape as the uprights and each rail comprises two similar channel members 4, each provided with the central longitudinal inwardly disposed dove-tailed channel portion 5 and with the off-set portions 6 provided for strengthening purposes. The inturned flanges 7 upon the rails 4 are similar to the in-turned flanges 8 upon the uprights extending inwardly beyond the channel portions 5.

One of the channel members 1 of each upright is provided at its upper and lower ends with attaching means for temporarily attaching the upright to the ceiling and the floor respectively. This attaching means preferably comprises an expansion bolt 100 which includes the split expansion sleeve 9 arranged to be located in a suitable socket in the ceiling or floor, a conical nut 10 being provided in said sleeve, the interior of said sleeve being preferably squared to conform with the shape of the nut. A lip 11 extends across the top of the sleeve and is arranged

to be engaged by the upper extremity of the bolt 12 upon which the nut 10 is mounted.

Upon the lower end of the bolt is provided a flattened portion 13 having an elongated countersunk slot 14 therein. This portion 13 of the bolt is arranged to be received between the channel portions 2 of the channel members 1 of each upright, a bolt 15 being passed through said slot, the head thereof being received within the countersunk portion of said slot, said bolt extending through a suitable aperture 16 in the channel portion 2 of one of the channel members, a nut 17 being placed upon the end of the bolt for securing the member 13 to the channel member.

A base board 18 is preferably provided at the bottom of the partition for the purpose of giving a finished appearance to the same and in order to provide means for varying the height of the partition to accommodate different conditions this base board is preferably made adjustable in height.

The base board proper comprises two side walls 19 spaced from each other by the upper and lower channel members 20 and the end channel members 21 which are spot welded or otherwise permanently connected to the side walls 19. The channel members 21 have central outwardly extending flanges 22 spot welded or otherwise connected thereto, these flanges being received between the flanges 8 of the uprights. The channel members 4^a of the lowermost connecting rails 35 of the partition are provided with downwardly disposed flanges 23 which are spot welded or otherwise connected to the flanges 7^a of said channel members.

The panels 24 or 25 which are formed of sheet metal or glass sash respectively are clamped between adjacent channel members of the uprights and cross rails. The sheet metal panels 24 comprise a flat rectangular sheet and the glass sash panels comprise a rectangular sheet metal frame 26 which is off-set at 27 in order to bring the glass in the center of the partition. An angle iron frame 28 is secured to the frame 26 in any suitable and well known manner and the glass panels 29 are attached thereto by means of putty 30 or the like.

The channel members 1 and 4 are provided at intervals with apertures 31 which receive the bolts 32, nuts 33 being provided upon said bolts for drawing said channel members tightly together and clamping the panels therebetween. For the purpose of giving the uprights and cross rails a finished appearance filler strips 34 of channel shaped cross section and formed of spring material are located in the dove-tailed channel portions 2 and 5 of the channel members forming the uprights and cross rails, these filler strips being preferably provided at their inner extremities with beads 35 arranged to

engage the inner walls of the dove-tailed channel portions in order to retain the strips therein as well as to permit of the strips being easily placed in position.

It will be evident from the foregoing description that a partition construction is thus provided which is simple and inexpensive to manufacture and erect and which may be easily and readily erected or knocked-down and replaced in a different location without injury to the partition or to the building within which it is erected.

We claim:

1. In a metallic partition, a hollow upright formed of two channel shaped members, each of said channel shaped members having a central, inwardly disposed portion, panels located between the channel members of said uprights and bolts located through the channel portions of the channel members of the uprights for clamping the upright together upon the edge portions of the panels, and filler strips located in said channel portions and covering said bolts.

2. In a metallic partition, a hollow upright formed of two channel shaped members, each of said channel shaped members having a central, inwardly disposed, dove-tailed channel portion, panels located between the channel members of the upright, bolts located through the channel portions of the channel members for clamping the upright together upon the edge portions of the panels, and channel shaped filler strips located within said dove-tailed channel portions and covering the bolts.

3. In a metallic partition, a hollow upright formed of two channel shaped members, each of said channel shaped members having a central, inwardly disposed, dove-tailed portion, panels located between the channel members of the upright, bolts located through the dove-tailed channel portions of the channel members for clamping the upright together upon the edge portions of the panels, and channel shaped filler strips provided with beads upon their inner edges located between said dove-tailed channel portions and covering the bolts.

4. In a metallic partition, the combination of a plurality of hollow uprights each formed of two channel shaped members, each of said channel shaped members having a central inwardly disposed channel portion, a plurality of cross rails located between the uprights, panels located between the channel members of said uprights and bolts located through the channel portions of the channel members for clamping the uprights together upon the edge portions of the panels and filler strips located in said channel portions.

5. In a metallic partition the combination of a plurality of hollow uprights each formed of two channel shaped members,

each of said channel shaped members having a central, inwardly disposed dove-tailed channel portion, a plurality of cross rails located between the uprights, panels located 5 between the channel members of said uprights and bolts located through the channel portions of the channel members for clamping the uprights together upon the edge portions of the panels said bolts being 10 located entirely within said dove-tailed channel positions.

6. In a metallic partition the combination of a plurality of hollow uprights each formed of two channel shaped members, 15 each of said channel shaped members having a central, inwardly disposed dove-tailed channel portion, a plurality of cross rails located between the uprights, panels located between the channel members of said uprights and bolts located through the channel portions of the channel members for clamping the uprights together upon the edge portions of the panels and filler strips 20 located in said channel portions.

25 7. In a metallic partition the combination of a plurality of hollow uprights each formed of two channel shaped members, each of said channel shaped members hav-

ing a central, inwardly disposed dove-tailed channel portion, a plurality of cross rails 30 located between the uprights, panels located between the channel members of said uprights and bolts located through the channel portions of the channel members for clamping the uprights together upon the edge portions of the panels and channel shaped filler strips provided with beads upon their inner edges located within said dove-tailed channel portions.

8. In a metallic partition the combination 40 of a plurality of hollow uprights made in halves, a plurality of hollow cross rails made in halves, channels located between the edges of the hollow uprights and cross rails, means for clamping said edges together upon the edge portions of the panels, base boards provided with flanges extending between the halves of the uprights and a downwardly disposed flange connected to each half of the lower cross rail and engaging 45 the sides of the base board.

In testimony that we claim the above, we have hereunto subscribed our names.

JOHN O. NYMAN.
JOHN P. PEARSON.
